COVERING FOR THE BOARD OF IRONING TABLES

Samuel A. Di Gesare, Buffalo, N. Y.

Application October 13, 1944, Serial No. 558,553

4 Claims. (Cl. 38—140)

1

This invention relates to a cover for an ironing board and more particularly to a board forming part of an ironing table. The object of this invention is to provide improved means for detachably securing a cover to the board so that the same will provide a smooth and even ironing surface and permit the cover to be readily applied to and removed from the ironing board.

In the accompanying drawings:

Fig. 1 is a vertical longitudinal section showing a cover made in accordance with this invention applied to an ironing board which forms part of a table having means for supporting the same on a floor.

Fig. 2 is a perspective view of the pad or cushion forming part of this cover applied to the ironing board and viewed from the underside thereof.

Fig. 3 is a similar view showing the blanket and pad of the covering applied to an ironing board and viewed from the underside thereof.

Fig. 4 is a fragmentary view similar to Fig. 3 but showing part of one of the rear flaps of the blanket detached from the adjacent part of the rear pocket of the blanket.

In the following description similar reference numerals indicate like parts in the several figures of the drawings:

As shown in Fig. 1, the ironing table in connection with which this invention is to be used, comprises a board 10 which is adapted to be supported in a horizontal operative position by means of a support attached to the underside of this board and resting at its lower end on the floor. In the drawings only one leg 11 of this support is shown, this being pivotally connected at its upper end with the rear part of the ironing board and a brace 12 which is connected with the underside of the front part of this board.

The ironing board is flat and comprises a comparatively wide rear part or body 13 having parallel longitudinal edges 14, a blunt rear transverse end 15 and a front part 16 having the form of a forwardly tapering neck the longitudinal edges 17 of which converge forwardly and the extreme front end of which is of rounded form, as indicated at 18 in Fig. 2.

In general the ironing board covering comprises a lower pad or cushion 19 and an upper blanket or facing 20. The pad or cushion 19 is preferably constructed of felt or the like and has substantially the same shape as the ironing board and adapted to cover the wide rear and narrowed front parts of the same.

In order to hold this pad or cushion against displacement on the ironing board, the rear end

2

of the same is provided on its underside with a rear pocket 21 which is adapted to receive the rear or blunt end portion of the ironing board and the front end of this pad is provided on its underside with a front tapering pocket 22 which is adapted to receive the tapering front end of the ironing board. These two pockets are preferably made of duck, canvas or drill material.

On the central part of the inner edge of the rear pocket the same is provided with a notch 23 which receives the upper end portion of the table leg 11 and thereby avoids interference between the latter and the covering when the same is applied to the ironing board.

10 The blanket of the ironing board cover also has the general form of the ironing board and comprises a relatively wide rear part 23 which extends over the wide rear part 13 of the pad or cushion and has parallel longitudinal edges 24 and a forwardly tapering front part 25 the longitudinal edges 26 of which converge forwardly so that the same is generally of V-shape. At its rear end, the wide rear part of the blanket is provided on its underside with a forwardly opening rear pocket 27 which is adapted to receive the rear end of the ironing board and the rear end of the pad or cushion, and at its front end the V-shaped part of the blanket is provided on its underside with a front pocket 28 which receives the front end of the neck of the ironing board and the corresponding front part of the pad.

15 On each of its opposite longitudinal edges the blanket is provided with a longitudinal flap including a rear part 29 which is turned downwardly around the longitudinal edges of the wide rear part of the ironing board and the adjacent part of the pad and also is turned inwardly and upwardly against the underside of the ironing board, as shown in Fig. 3. These rear parts 29, 29 of the two longitudinal flaps of the blanket are folded against the undersides of the adjacent side parts of the rear pocket 27 and are detachably connected therewith by means of press buttons or snap-ons each of which preferably consists of a female member or socket 30 which is arranged on the inner side of the rear end portion of the respective rear flap and engaged with a male member or head 31 secured to the outer side of the adjacent part of the rear end pocket of the blanket, as shown in Fig. 3.

20 Each of the longitudinal flaps also includes a front portion 32 along the forwardly converging longitudinal edges of the tapering front part of the blanket, the front portions 32, 32 of these

longitudinal flaps being turned downwardly around the corresponding converging edges of the ironing board and the pad and against the underside of this pad.

For the purpose of causing the longitudinal flaps of the blanket to fit closely to the ironing board and the pad, and remain firmly in engagement therewith, each longitudinal flap is provided between its front and rear portions 29 and 32 with a dart 33 which draws the respective edges 10 of these front and rear portions 29 and 32 of each flap together so that they form an obtuse angle with each other.

Means are provided for stretching the two longitudinal flaps 29, 32 longitudinally, and also drawing the forward ends of these flaps inwardly relative to the edge portions of the ironing board.

The preferred means for accomplishing this purpose comprises two oblique tabs 34, 34 each of which is arranged at an angle relative to the longitudinal axis of the ironing board, pad and blanket and also at an angle relative to the respective front flap 32 and each of these tabs being preferably secured at its rear end to the inner front corner of the respective front flap.

In the assembled position of the parts, the two tabs 32 overlie one another in a manner resembling a cross and each of these tabs is detachably connected at its free front end beyond the front side of the other tab with the front pocket 38. The means for thus detachably connecting each of these tabs with the front pocket 38 consists of a press button or snap-on fastener having a male member or head 35 secured to the pocket 38 and a female member or socket 36 secured to the free end of the respective tab and engaging over the companion male member, as shown in Figs. 1 and 3.

With the rear end portions 29 of the side flaps secured by the snap fasteners 30, 31 to the rear pocket 27, when each tab 34 is drawn forwardly to engage its snap fastener head 36 with the counterpart snap fastener head 35 on the pocket 38, a longitudinal pull is exerted on the side flap 29, 32 the full length thereof. Since the edge of this longitudinal side flap 29, 32 is formed to provide an obtuse angle by the provision of the dart 33, this longitudinal pull tends to straighten this obtuse angle and hence draw the longitudinal side flap 29, 32 inwardly toward the longitudinal axis of the board along the entire length of the flap. With both side flaps so secured, it will be seen that the edges of the blanket are drawn transversely inward to fit snugly the edges of the ironing board.

Further, when the tabs are attached by their press buttons with the pocket 38, a diagonal forward and inward pull is produced on the longitudinal flaps 29, 32 on each longitudinal edge of the ironing board toward the opposite longitudinal edge of the same, thereby further insuring that the longitudinal side flaps of the blanket are drawn tightly against the respective longitudinal edges of the ironing board. The combined longitudinal and transverse forces exerted by the tabs 34 thereby insures that the blanket is stretched in all directions and all wrinkles therein are removed, thereby maintaining the same in a smooth and even condition and best suited for producing good ironing work on the same.

The body of the blanket and its pockets, flaps and tabs are made of strong, flexible material such as duck, canvas or drill material.

The rear pocket of the blanket is provided on the central part of its inner edge with a notch

37 which registers with the corresponding notch 23 in the rear pocket of the pad and receives the upper portion of the table leg 11 and avoids interference between this leg and the blanket.

While the invention has been described as applied to a household ironing board it is obvious that it can also be used in conjunction with commercial pressing machines of any type to cover both the upper and lower buck of the pressing machine, the word "ironing board" as used in the following claims, including either buck of a pressing machine.

This ironing board covering is not only very strong and durable, but the same can also be constructed of a minimum amount of material. It also can be easily applied to an ironing board and is held on the board reliably and firmly so as to maintain the blanket of the covering always in a smooth and unwrinkled condition.

I claim as my invention:

1. A cover for a flat ironing board having a body which is relatively wide and having a neck which tapers lengthwise toward the front end of the body, comprising a blanket having a body adapted to extend over the body and neck of the ironing board, a rear pocket arranged on the rear end of the blanket body and adapted to receive the rear end of the board, a front pocket arranged on the front end of said blanket body and adapted to receive the front end of said neck, longitudinal side flaps arranged on the longitudinal edges of the blanket body intermediate said pockets and adapted to fold around the longitudinal edges of the ironing board, fastening means for detachably connecting the rear ends of said longitudinal flaps with said rear pocket, oblique tabs arranged on the front ends of said longitudinal flaps and each extending diagonally forwardly and inwardly relative to the longitudinal axis of the blanket, and fastening means for detachably connecting each of the tabs with the front pocket of the blanket body.

2. A cover for a flat ironing board having a body which is relatively wide and having a neck which tapers lengthwise toward the front end of the body, comprising a blanket having a body adapted to extend over the body and neck of the ironing board, a rear pocket arranged on the rear end of the blanket body and adapted to receive the rear end of the board, a front pocket arranged on the front end of said blanket body and adapted to receive the front end of said neck, longitudinal side flaps arranged on the longitudinal edges of the blanket body intermediate said pockets and adapted to fold around the longitudinal edges of the ironing board, fastening means for detachably connecting the rear ends of said longitudinal flaps with said rear pocket, oblique tabs arranged on the front ends of said longitudinal flaps and each extending diagonally forwardly and inwardly relative to the longitudinal axis of the blanket and each overlying the other tab so as to form a cross therewith, and fastening means for detachably connecting the front end of each of said tabs with said front pocket at a point beyond the other tab.

3. A cover for a flat ironing board having a body which is relatively wide and having a neck which tapers lengthwise toward the front end of the body, comprising a blanket having a body adapted to extend over the body and neck of the ironing board, a rear pocket arranged on the rear end of the blanket body and adapted to receive the rear end of the board, a front pocket arranged on the front end of said blanket body and adapted

to receive the front end of said neck, longitudinal side flaps arranged on the longitudinal edges of the ironing board, fastening means for detachably connecting the rear ends of said longitudinal flaps with said rear pocket, oblique tabs arranged on the front ends of said longitudinal flaps and each extending diagonally forwardly and inwardly relative to the longitudinal axis of the blanket, and fastening means for detachably connecting each of the tabs with the front pocket of the blanket body, each of said longitudinal side flaps being provided intermediate its ends with a dart whereby the edge of each longitudinal side flap is in the form of an obtuse angle, the forwardly stretching force of the corresponding tab tending to straighten said obtuse angle and to draw said longitudinal flaps toward said longitudinal axis.

4. A cover for a flat ironing board having a body which is relatively wide and having a neck which tapers lengthwise toward the front end of the body, comprising a blanket having a body adapted to extend over the body and neck of the ironing board, a rear pocket arranged on the rear end of the blanket body and adapted to receive the rear end of the board, a front pocket arranged on the front end of said blanket body and adapted to receive the front end of said neck, longitudinal side flaps arranged on the longitudinal edges of the blanket body intermediate said pockets and

adapted to fold around the longitudinal edges of the ironing board, fastening means for detachably connecting the rear ends of said longitudinal flaps with said rear pocket, and fastening means for detachably connecting the front end of each longitudinal side flap with the front pocket of the blanket body and exerting a forwardly stretching force on each longitudinal side flap, each of said longitudinal side flaps being provided intermediate its ends with a dart whereby the edge of each longitudinal side flap is in the form of an obtuse angle, the said forwardly stretching force of said fastening means tending to straighten said obtuse angles and to draw said longitudinal flaps toward the longitudinal axis of said blanket.
